UNITED STATES PATENT OFFICE

ALBERT PFLUEGER, OF MIAMI, FLORIDA

METHOD AND MEANS FOR MOUNTING FISH AND VARIOUS SPECIMENS HOLLOW

Application filed December 30, 1931. Serial No. 583,965.

This invention relates to a method of mounting fish and other specimens, the general object of the invention being to provide a stiffening medium on the inner face of the skin so that this medium will hold the skin in position after the specimen has been shaped in a mold and over a filler while the stiffening material is drying and hardening. Thus after the filler is removed the specimen will be hollow and will be supported in its natural state by the hardened stiffening medium placed on the inner surface.

The invention, together with its many objects and advantages will be best understood from a study of the following description, taken in connection with the accompanying drawing:

Figure 1 is a transverse sectional view showing the parts initially assembled before the application of a filling, and in accordance with the present invention.

Figure 2 is a similar view showing the position of the parts subsequent to the application of the filling.

Figure 3 is a view similar to Figure 2 with the specimen removed from the mold and the filling drained from the mounted specimen.

Figure 4 is a top plan view of a portion of a stiffening medium.

Figure 5 is a fragmentary transverse sectional view taken substantially on the line 5-5 of Figure 4.

In carrying out my invention I provide a mold 1 of suitable shape, in the present instance the mold being especially designed for use in the mounting of a fish specimen. As shown the skin of the specimen 2 has a portion thereof placed lengthwise in the mold, and then, to the inner side of the skin of the specimen is applied means for substantially stiffening the skin. In the present instance to stiffen the skin 2 I provide one or more sheets 3 of cloth, in the present instance a wire cloth is shown. To one side of the cloth 3 I apply a coating 4 of plaster, papier-mâché, celluloid or any other substance which hardens when it becomes dry. The substance 4 may be applied to the cloth 3 to the thickness desired.

The strips 3 are preferably narrow, and the strips to a sufficient number are arranged transversely of the skin 2 of the specimen with the plastic substance 4 presented to the inner side of the skin to adhere thereto as suggested in Figure 1.

Subsequent to the application of the strips or sheets 3 to the inner side of the skin a filler 5 of sawdust, sand, earth or other material which may be readily removed from the specimen when the latter is mounted and dry, is placed on the part of the specimen fitted within the mold 1 as suggested in Figure 2 after which the remaining side of the skin is then folded over the filler 5 as suggested in Figure 2. After this is done the meeting edges of the specimen are suitably secured together if necessary or desired.

With this step in the process or method completed, the specimen is then removed from the mold 1 and placed on a drying board. Subsequent to a thorough drying of the mounted specimen the filler 5 may be removed in a manner well known to those skilled in the art, such as by leaving an opening in the specimen through which the filler can be removed.

By reason of the stiffening means consisting of the sheet 3 and adhesive substance 4, it is apparent that the skin of the specimen will maintain its rigidity after the filler 5 has been removed and the specimen subsequent to the removal of the filler is now ready for finishing, a process also well known to those skilled in the art and not of the essence of the present invention.

It will be apparent that the strip 3 having the adhesive material 4 applied to one side thereof forms the cast for the skin 2 of the specimen as required in order to give the mounted specimen the necessary life like appearance.

While I have herein shown and described the path for the specimen as consisting of one or more sheets 3 having a substance 4 applied thereto, it is to be understood that I do not wish to limit myself to the use of the cloth 3 since the same result may be obtained by the use of the substance 4 applied to the inner side of the skin. It is also to be understood that I claim all forms of the invention.

to which I am entitled, intending in no wise to restrict the invention except as the prior art and the scope of the appended claims may require.

5 Having thus described my invention, what I claim as new is:

1. A method for mounting specimens hollow, consisting of applying a plastic substance to the inner side of the skin of the specimen, and subsequently stretching the skin over a filler, and finally removing the filler subsequent to the drying of the plastic material.

2. A method for mounting specimens comprising placing a portion of the skin of the specimen in a mold, then treating the inner surface of the skin with plastic material, which, when dry, will hold the skin in shape, then placing a filler on that portion of the skin in the mold and folding the remaining part of the skin over the filler and finally removing the filler after the plastic material has dried.

25 In testimony whereof I affix my signature.

ALBERT PFLUEGER.
